UNITED STATES PATENT OFFICE.

JOHN J. DUCK, OF TOLEDO, OHIO.

ELECTRIC SWITCH.

Application filed November 19, 1917. Serial No. 202,730.

To all whom it may concern:

Be it known that I, JOHN J. DUCK, a citizen of the United States of America, residing at Toledo, Lucas County, Ohio, have invented new and useful Electric Switches, of which the following is a specification.

This invention relates to electric switches, particularly of the quick throw type.

This invention has utility in its general adaptation, especially for compact grouping of switches even in standard boxes.

Referring to the drawings:

Fig. 1 is a plan view of a pair of quick throw switches in accordance with the invention showing the assembly thereof in a single housing chamber in the space usual for but a single switch;

Fig. 2 is a section on the line II—II, Fig. 1, looking in the direction of the arrow, one of the push buttons being shown depressed;

Fig. 3 is a bottom plan view of the device grouping of Fig. 1, the floor of the housing being removed and one of the transverse members having its elements in section;

Fig. 4 is a section, partially on the line VI—VI, Fig. 3;

Fig. 5 is a fragmentary perspective view of the release device for the quick throw action of the switch;

Fig. 6 is a detail in side elevation of the ratchet, or step by step rotation drive feature.

Fig. 7 is a side elevation on an enlarged scale of one of the switches of Fig. 2; and

Fig. 8 is a section on the line VIII—VIII, Fig. 7.

The housing 1 of insulation material, as a porcelain unit or fibre may be of form and contour for mounting in standard boxes by screws through the holes 2 in the cross clip or guide 3, which guide 3 is anchored to the housing by the screws 4. A usual plate or shield may serve as a flush closure by having its screws engage the openings 5. Such plate is provided with openings registering with the openings 6 in the guide 3 for the push buttons 7, 8.

Each push button is provided with an offset or curved extension or stem 9 carrying the pivot pin 10. The pivot pin 10 is engaged by the link 11 loosely mounted on the shaft 12. In the grouping of the two switches, one shaft 12 has the mounting

bracket 13 and the other has the mounting bracket 14 seating over the bracket 13, and the two anchored in position to the guide or member 3 by the pair of screws 15.

The pin 10 has mounted loosely thereon between the extension 9 and the link or arm 11, the pawl 16, normally thrown by the spring 17 to ride upon the ratchet wheel 18 fast on the shaft 12. A torsion spring 19 in the form of a spiral is about the shaft 12 with one end thereof engaging the link 11 and the other end thereof engaging the mounting bracket 13 or 14 for the particular shaft 12. This torsion spring 19 normally resets the push buttons 7, 8, causing such push buttons when depressed and released automatically to return to outwardly projected initial position.

The shaft 12 has a pair of flattened portions 20, Fig. 5, embraced by a cam 21 and serving to lock such cam for rotation with the shaft 12. The cam 21 is disposed in the slot 22 of the rock arm 23 having the pivot bearing 24 mounted eccentrically in the disk or member 25. This member 25, loosely mounted on the shaft 12 is connected by the torsion spring 26 and key 27 to be placed in action upon upward thrust of a push button to rotate a shaft 12, the spring 26 is at once placed under torsion, for the member 25 is held from rotation by the member 23 having its dog 28 engage the teeth of the fast toothed member 29 as a ratchet fixed with the bracket 13 or 14, and accordingly held from rotation with the shaft 12. However in this action of the push button in rotating the shaft 12, the cam 21 is gradually shifting the rock arm or member 23, so that approximately just before full thrust inward of the push button, the dog 28 clears the four toothed ratchet 29 and the winding up of the spring 26 effects a quick 90° throw of the member 25. The member 25 has a pair of diametrically spaced outwardly projecting arms 30 having thereon insulation 31 carrying clear from shaft 12 and the moving parts a pair of opposing diametrically extending spring fingers 32 as switch closing elements.

The switch closing electricity conducting elements 32 may operate on diametrically disposed terminals 33 as an independent complete single pole switch. A terminal

33 may be disposed to have a terminal 34 opposite thereto carrying a supplemental terminal 35 at 90° therefrom in the path of the elements 32. Diametrically as to the terminal 35 the disposal of a terminal 36 permits the elements 32 in their step by step rotation to engage terminals at each step, as in a three point switch. Accordingly, so far as the push button, and the parts moved thereby, the elements for electric control may be different or similar types of switches in the common standard size housing, say two single pole switches, a single pole and a three way switch, or even two three way switches.

With any of the above combinations of switches in the single housing chamber, there is but the simple or single pair of push buttons occupying but the usual single box wall space. There is accordingly economy in box expense as well as plates, with the range of possibilities for equipment selection in the box as broad as if two boxes were used, or a double box with double plate.

Considering the thrust direction of the push button as its axis, and looking at the push button from its end of the grouping toward the center of the grouping pair, the mounting of the driven member and its coacting parts to be actuated is in the upper left hand quadrant. The shaft 12 is parallel to the crosswise extending side of the quadrant and extends toward the other side of the quadrant. This semi-symmetrical disposition of the driven member in its extent transversely of its actuating member or push button, readily lends itself to interchangeability of the push button sets. As these push button and actuated member are in identical sets as to structure, except for the brackets 13, 14, there is great manufacturing advantage in thus reducing the kinds of sets to one for the full range of installations. The electric current carrying terminals and elements are as remotely disposed as the full limit of the housing permits, and the electrical safety is at a maximum. Even with the range of terminals and utilities, there is no crowding or encroachment of one set and its terminals upon the other set and its separate terminals. Each switch is independent of the other in its installation, structure and operation. This means that terminals of opposite polarities may be used with two single pole switches.

What is claimed and it is desired to secure by Letters Patent is:

1. In electric switch structures, a housing providing an oblong chamber, a push button mounted to operate in the chamber centrally of an end thereof, a driven member, actuating means from the push button to the member, a button guiding link between the button and member in addition to said actuating means, and mounting means for the driven member, said driven member being positioned by said housing on one side of a diameter of the housing through the button, whereby said structure may be placed in either of two positions in said housing, the button in one position being spaced from that of the other position, with the driven member oppositely disposed and aligned in one position as to the other position.

2. A switch housing, a mounting plate for the housing extending across the housing, guide opening through the mounting plate, bracket means anchored by the mounting plate and providing bearings transversely of the housing between the guide openings, a push button mountable in either guide opening, shaft means mountable in one bearing to align with the other bearing as an independent bilateral construction as to such other bearing, a link between said push button and the shaft means for directing push button travel, a ratchet wheel on the shaft means, and a dog carried by the push button to actuate said ratchet wheel.

3. A switch housing, a mounting plate for the housing extending across the housing, adjacent parallel guide openings through the mounting plate, bracket means anchored by the mounting plate and oppositely extending to provide bearings transversely of the housing between the guide openings, a pair of terminals eccentrically of each bearing, and duplicate switch actuators, one for each bearing and its pair of terminals, each actuator including a push button, shaft means, and terminal coacting means, one of said push buttons being mounted in one of said guide openings and the other push button being mounted in the other guide opening, and one shaft means being mounted in one bearing and the other shaft means being mounted in the other bearing.

In witness whereof I affix my signature.

JOHN J. DUCK.
